ROOF FLASHING

Filed Dec. 26, 1925

Patented June 1, 1926.

1,587,250

UNITED STATES PATENT OFFICE.

ROBERT J. STEPHENSON, OF CHICAGO, ILLINOIS.

ROOF FLASHING.

Application filed December 26, 1925. Serial No. 77,846.

This invention relates to roof flashings, adapted to maintain water-tight joints between a roof and a pipe, such as a ventilating pipe, projecting upwardly therethrough.

These devices commonly comprise a flat base plate which is anchored in or upon the roof materials, and a sleeve member projecting from the base, the free end of the sleeves snugly surrounding the pipe and being calked or otherwise secured thereto to maintain a tight joint. The pipe is usually supported from below, independently of the roof, and if the roof should settle an appreciable amount, as it often does in time, the joint between the sleeve and the pipe will be broken away and leakage will occur.

The principal object of the present invention is to provide a roof flashing which will permit limited relative vertical movement between the roof and pipe without disturbing the joints between the flashing and the pipe or between the flashing and the roof. This is accomplished by making the flashing of two telescopic sections, one permanently secured to the roof and the other permanently secured to the pipe, there being a limited longitudinal movement permitted between the telescopic sections to allow for the settling of the roof.

Another object is to provide a roof flashing which is adapted for use with roofs of various inclinations, as well as pipes varying somewhat in size.

Another object is to provide a roof flashing in which the pipe engaging collar is adjustable in diameter to fit pipes of different sizes, or to permit the collar to be passed over enlargements or projections of the pipe when the pipes are being assembled.

Other objects and advantages of this invention will be apparent from the following detailed description of one approved form of the device.

In the accompanying drawings:

Fig. 1 is a perspective view of the improved roof flashing in use.

Fig. 2 is a central vertical section through the improved roof flashing.

Fig. 3 is a plan view of the pipe-engaging collar.

Referring first more particularly to Fig. 1, the foundation of a roof is indicated at 1, the roof having a covering, for example the shingles 2, for excluding water. As indicated, a portion of the shingle cover-

ing 2 has been removed to disclose the base plate 3 of the roof flashing, which base plate will ordinarily be anchored between the roof 1 and the shingles 2. Obviously, any other type of roof covering might be used in lieu of the shingles. The base 3 is formed of sheet metal, and preferably stamped integrally therefrom is a projecting tapered sleeve portion 4, terminating in a cylindrical portion 5. The sleeve portions 4 and 5 extend at an angle to the perpendicular from the plane of base plate 3, for reasons hereinafter specified. A cylindrical sleeve member 6 is secured to the cylindrical sleeve portion 5 by a crimping operation, thereby forming an outwardly projecting flange 7, on the continuous tube formed by members 5 and 6. The cylindrical portion 6 is practically a continuation of the cylindrical portion 5, and might be made integral therewith, it being formed from a separate piece of metal simply for convenience of construction. An out-turned flange 8 is formed at the upper free end of tube 6. A second tubular sheet metal member 9 has an inner diameter sufficient to enclose the periphery of flange 8, and terminates at its lower end in an inturned flange 10 adapted to closely surround the tubular member 6 beneath the flange 8. Obviously, the telescopic tubular members 6 and 9 are capable of relative sliding movements longitudinally of the axis of the two tubular members, this relative movement being limited by the engagement of flange 10 with either of the flanges 7 or 8 on the inner tube 6. The interlocking engagement of the sleeve portions 6 and 9, provided by the flanges 8 and 10, will prevent complete separation of these members, whereby handling and shipping of the flashing, as a unit, is facilitated. These interlocking flanges also help to prohibit leakage into the flashing at this extensible joint.

A collar 11 of soft malleable metal, such as lead, is secured to the upper edge of cylindrical member 9 by being cast or otherwise formed about an irregular flange 12 at the upper edge of the cylindrical member. The collar 11 is of hollow conical form, and preferably tapers from a relatively thick lower edge, where it is secured to tube 9, to a relatively thin upper pipe engaging edge 13. The diameter of the opening in the upper edge 13 of the collar is substantially the same as that of the pipe

14, and a tight joint is formed between the pipe and collar by calking the edge 13 against the pipe, soldering it thereto, or any other suitable means of connection.

5 Although the collar 11 may be made in the form of a continuous ring, or annular member, it is preferably split longitudinally at one side along a diagonal line, as at 16, to provide overlapping end portions so that 10 the diameter of the ring may be slightly varied while still maintaining a tight joint at the split. Any suitable means may be employed for holding the split ends of the ring adjustably in engagement with one 15 another, for example, angle plates 15 may be secured to the ends of the ring or collar adjacent the split 16, the angle plates 15 being connected by an adjustable screw bolt 17. By opening the split in the collar 11, 20 it is possible to pass the collar over outstanding flanges or other projections on the pipe section 14, when the pipes are being assembled, and the adjustable diameter of the opening in the collar permits its use with 25 different sizes of pipe 14, within a limited range.

As has been previously noted, the tapered sleeve portion 4 extends at an angle to the perpendicular from base plate 3, so that 30 the axis α (Fig. 2) of the tubular sleeve portions 6 and 9, will be at an angle to this perpendicular. It will also be observed that the diameters of the tubular sleeves 6 and 9 are considerably larger than the diameter 35 of the pipe 14. The pipe 14 will ordinarily be positioned vertically, and the roof 1 will ordinarily be slanting at an angle to both the horizontal and the vertical, and the features noted just above are for the purpose 40 of adapting this roof flashing to roofs of various inclinations. The narrow edge 13 of the collar 11 is rounded so that some freedom of movement is permitted the pipe section 14 within the collar, and the axis of 45 the pipe 14 need not coincide with the axis α of the tubes 6 and 9, but the pipe may be positioned at various angles with respect to this axis as indicated by the dotted lines a and b in Fig. 2. This feature adapts the 50 flashing for use on roofs varying considerably in their inclination to the horizontal. The split collar 11 (if this feature is added) permits a greater range of variation in the size of the pipe 14 with which the device 55 may be used, and also facilitates the assembling of the flashing on a pipe having flanges or other outstanding projections.

When the device is positioned for service, 60 the base plate 3 is anchored to the roof 1, and the pipe 14 is positioned through the tubular sleeve portions and the collar 11, with the cylindrical members 6 and 9 telescoped, so that flange 10 is against or adjacent to the lower flange 7 on tube 6. The 65 upper edge 13 of collar 11 is then calked or

otherwise permanently secured against the pipe 14 to form a water-tight joint between these two members. If now the roof 1 should settle with respect to the pipe 14, carrying down with it the base plate 3 of 70 the flashing, it will not break loose the joint between the collar 11 and the pipe 14, as happens with roof flashings of the ordinary type, but the tubular members 6 will simply slide down within the upper tubular 75 member 9 without disturbing this tubular member 9 and the collar 11 which remains securely anchored to the pipe 14. Of course, vertical movements of the pipe 14 with relation to the roof 1, if such should take place, 80 will also be permitted by virtue of this telescopic connection between the two cylindrical portions of the roof flashing.

The base plate 3, tapered sleeve 4 and cylindrical sleeve 6, might be made of several connected parts, or all of one integral member, and the collar 11 may take other forms than that here illustrated, without departing from the essential features of this invention, as described hereinabove, and 90 specified in the claims appended hereto.

I claim:

1. A roof flashing comprising a base in the form of a flat metal plate, having a sleeve extending from one face thereof, and an inwardly projecting soft metal collar at the free end of the sleeve for snugly engaging a pipe, the sleeve comprising interlocked telescoping cylindrical sections of substantially greater diameter than the 100 pipe.

2. A roof flashing comprising a base in the form of a flat metal plate having a sleeve extending from one face thereof, and a soft metal collar at the free end of the sleeve for snugly engaging a pipe, the sleeve being extensible to permit relative movements of the base and the pipe, and the collar being of variable inner diameter.

3. A roof flashing comprising a base in the form of a flat metal plate having an extensible sleeve extending from one face thereof, and a soft metal split sleeve at the free end of the collar adapted to engage about a pipe, and means for adjustably connecting the ends of the sleeve.

4. A roof flashing comprising a base in the form of a metal plate, having a sleeve extending from one face thereof, the sleeve comprising two interlocking telescopic sections and a soft metal collar at the free end of the sleeve for snugly engaging a pipe.

5. A roof flashing comprising a base in 125 the form of a metal plate having an integral sleeve extending from one face thereof, the sleeve comprising two interlocking telescopic sections and a soft metal collar at the free end of the sleeve for snugly engaging a pipe.

6. A roof flashing comprising a base in the form of a metal plate, having a sleeve extending from one face thereof, the sleeve comprising two telescopic sections, means for limiting the relative movement of the sections axially of the sleeve, and a soft metal collar at the free end of the sleeve. 55
7. A roof flashing comprising a base in the form of a metal plate, having a sleeve extending from one face thereof, the sleeve comprising two telescopic sections, means for limiting the relative movement of the sections axially of the sleeve, a soft metal collar at the free end of the sleeve and means for varying the inner diameter of the collar. 60
8. A roof flashing comprising a base in the form of a metal plate, having a tapered sleeve extending at an angle from the face thereof and terminating in a cylindrical portion, a second cylindrical member telescopically connected with the first member for movement longitudinally of the axis of the sleeve, means to prevent complete separation of the two sleeve members, and a soft metal collar at the free end of the second member for snugly engaging a pipe. 70
9. A roof flashing comprising a base in the form of a metal plate, having a sleeve extending at an angle from one face thereof and terminating in a cylindrical portion, a second cylindrical sleeve member telescopically connected with the first member, the two members having flanges which engage to limit the relative movement of the members longitudinally of the axis of the sleeve, and a soft metal collar at the free end of the second sleeve member for snugly engaging about a pipe. 75
10. A roof flashing comprising a base in the form of a metal plate, having a sleeve extending at an angle from one face thereof and terminating in a cylindrical portion, a second cylindrical sleeve member telescopically connected with the first member, the two members having flanges which engage to limit the relative movement of the members longitudinally of the axis of the sleeve, and a soft metal collar of adjustable inner diameter at the free end of the second sleeve member for snugly engaging about a pipe. 80
11. A roof flashing comprising a base in the form of a metal plate, having a sleeve extending at an angle from one face thereof and terminating in a cylindrical portion, a second cylindrical sleeve member surrounding the outturned flange and having an inturned flange engaging beneath the first flange and slidably along the first cylindrical portion, and a soft metal collar at the free end of the second cylindrical member for snugly engaging a pipe. 85
12. A roof flashing comprising a base in the form of a metal plate, having a sleeve extending at an angle from one face thereof and terminating in a cylindrical portion having an outturned flange at its free end, and a second outturned flange intermediate its length, a second cylindrical sleeve member having an inturned flange slidable along the first cylindrical member between the outwardly projecting flanges, and a soft metal collar at the free end of the second cylindrical member for snugly engaging a pipe. 90
13. A roof flashing comprising a base in the form of a flat metal plate having a sleeve extending from one face thereof, an inwardly tapering soft metal split collar at the free end of the sleeve for engaging about a pipe, the ends of the split collar being oppositely beveled and overlapping one another, and means for adjustably connecting the split ends of the collar. 95
14. A roof flashing comprising a base in the form of a flat metal plate having a sleeve extending at an angle from one face thereof, an inwardly tapering soft metal collar at the free end of the sleeve for snugly engaging about a pipe, the pipe-engaging end of the collar being in the form of a split ring with overlapping ends, and means for adjustably connecting the split ends of the collar. 100
15. A roof flashing comprising a base in the form of a flat metal plate having a sleeve extending at an angle from one face thereof, an inwardly tapering soft metal collar at the free end of the sleeve for snugly engaging about a pipe, the collar being split longitudinally at one side and provided with overlapping portions at the split to permit a variation in the diameter of the pipe-engaging end of the collar, and means for adjustably connecting the split ends of the collar. 105
